RIFLE, STOCK, RECEIVER, AND TRIGGER GUARD ASSEMBLY

Original Filed July 29, 1939 2 Sheets-Sheet 2

UNITED STATES PATENT OFFICE

2,364,549

RIFLE, STOCK, RECEIVER, AND TRIGGER
GUARD ASSEMBLY

John D. Pedersen, Jackson, Wyo.

Original application July 29, 1939, Serial No. 287,221. Divided and this application March 13, 1943, Serial No. 478,997

4 Claims. (Cl. 42—75)

This application is a division from my copending parent case Serial No. 287,221, filed July 29, 1939, Patent No. 2,330,737, dated September 28, 1943, and the invention herein relates more particularly to the means for assembling the stock, receiver, and trigger guard of the rifle shown in said parent case.

In the drawings,

Fig. 1 is a longitudinal section through the receiver and part of the stock and barrel of the rifle of the present invention, the bolt and much of the interior mechanism of the rifle mounted on these parts being removed for better illustration;

Fig. 2 is a top view of the receiver;

Fig. 3 is a right side view of the guard assembled to the receiver, the intervening stock being omitted;

Fig. 4 is a section through the receiver, anchor, and guard, on section 4—4 of Fig. 3;

Fig. 5 is a section through a portion of the guard and the receiver on section line 5—5 of Fig. 3;

Fig. 6 is a section through a portion of the guard and the receiver on line 6—6 of Fig. 3; and

Fig. 7 is a fragmentary section on line 7—7 of Fig. 1 on a slightly smaller scale, showing the stock as embraced by the receiver and guard.

Referring to Figs. 1, 2, and 3, the receiver on the rifle is indicated at 1, the barrel 2, stock 46, and the trigger guard 101. The shape of the receiver is shown clearly in Figs. 2 and 3 and its forward end is formed with a well-like passage 4 therethrough constituting the magazine chamber adapted to receive a clip of cartridges (not shown). The barrel 2 is screw threaded into the receiver as indicated at 2a.

The stock 46 of the rifle is of the usual wood formation and is only partially shown in the present case in section, reference being had to applicant's copending case for disclosure of the complete stock. This stock 46 is embraced or clamped in a special manner as hereafter described between the receiver 1 which is on the upper side of the stock, and the trigger guard 101 which is on the lower side of the stock.

As shown in Fig. 1, anchor 50 is seated in a transverse slot 89 of the stock 46. The anchor screw 90 drawing against the anchor nut 91 secures the anchor firmly to the stock. The anchor carries a transverse slot 92 which fits the recoil lugs 93, 94 of the receiver 1 and holds the receiver against recoil or end movement with respect to the stock. (Figs. 3 and 4.)

The head 95 of the anchor screw 90 draws against the bottom of the anchor slot 92. The lower faces 96, 97 of the receiver recoil lugs 93 and 94 bear against the same surface of the anchor slot. As the underhead length of the anchor screw may be accurately fabricated it follows that the distance from the faces 96, 97 of the receiver recoil lugs 93, 94 to the lower end 98 of the anchor screw is constant (when the stock is firmly clamped between the anchor 50 and the anchor nut 91), regardless of the expansion or shrinkage of the wooden stock. As the lower end 98 of the anchor screw forms a stop for the rear end of the guard, Figs. 1 and 4, a spacer of constant length is thereby provided as between the rear ends of the receiver and of the guard. This arrangement enables the detachable guard to be assembled to the receiver with uniform precision regardless of expansion or shrinkage of the wooden stock.

The receiver is provided with a transverse groove 99 near its front end, into which the tenon 100 of the guard 101 engages as in Fig. 3. The receiver also carries a pair of ribs 102, 103 which project downwardly between the side wall shoulders 104, 105 of the guard 101 to hold the guard in correct lateral alignment with the receiver, Fig. 6. The receiver is formed with a pair of sockets 106, 107, Figs. 3 and 5, which open downwardly and rearwardly. Two trunnions or laterally projecting pins 110, 110a on rear vertical extensions 108, 109 of the guard engage in the sockets 106, 107, to accurately position the guard with respect to the receiver. The length of the anchor screw 90 is such that the rear end of the guard abuts the end 98 of the anchor screw just before the guard trunnions 110, 110a are moved upward to their seats in the receiver sockets 106, 107. When the trunnions are moved upward to their seats, the rear end of the guard, having a limited flexibility, is sprung slightly with respect to the remainder of the guard. As the trunnions 110, 110a are moved upward to their seats in the receiver sockets 106, 107, the guard tenon 100, having previously been entered into the receiver groove 99 is moved forward to full engagement with the receiver groove, due to the forwardly inclined path of the guard trunnions as controlled by a pair of cam surfaces 50 such as 111, which lead into the sockets 106, 107, Fig. 3. When the guard trunnions 110, 110a are moved downwardly out of the receiver sockets 106, 107, the guard at the same time is moved toward the rear, as controlled by the cam surface 112 which is an integral part of the guard

wall 108 riding on the inclined cam surface 113 formed on a web of the receiver, see Fig. 1, thus withdrawing the tenon 100 from the receiver groove 99. The rear end of the guard is positioned laterally in the receiver by having its rear vertical extensions 108, 109 engaged between the receiver side walls 114, 115 as shown in Figs. 3 and 5.

A latch hook 116, Fig. 1, for retaining the guard in place, is detachably carried on the hook pin 117, which is pivotally mounted between the side walls 118, 119 of the guard. The face 120 of the latch hook engages over the notch shoulder 121 of the receiver, Fig. 1, to hold the guard firmly upward in the receiver. The hook face 120 is a slow cam with "draw" sufficient to tighten the guard to the receiver despite small variations as between the affected surfaces. The latch hook is provided with a slot 122 occupied by the key 123 integrally formed on the hook pin 117 so that the latch hook may be rocked by means of the outside handle 124 on the hook pin 117. Fig. 3 shows in solid lines the handle 124 in the position of the latch hook engaged with the notch shoulder 121 of the receiver, and the handle (dotted) in the position of the latch hook disengaged from the shoulder 121 of the receiver preparatory to detaching the guard from the receiver.

The latch hook is provided with an incline 131 which is "ridden down" by the incline 132 of the receiver, when the guard is being assembled to the receiver. One end 133 of a double ended spring 134 engages a notch seat 130 in latch hook 116 and constantly forces the hook into engagement with the notch shoulder 121 of the receiver, Fig. 1.

The tenon 100 of the guard, engaged in the slot 99 of the receiver, forms a fulcrum around which the guard swings as its rearward end is assembled upward into the receiver. This swinging of the guard provides a leverage to compress the stock shoulders 135, 136 between the receiver shoulders 137 and the guard shoulders 138, see Fig. 7.

I claim:

1. In a rifle in combination, a receiver, a trigger guard, means for detachably mounting said guard on said receiver comprising a tenon and groove connecting means between the receiver and front end of the guard and serving as a fulcrum for swinging said guard into position, a pin and socket connecting means between said receiver and an intermediate portion of said guard, an abutment having a fixed relation to said receiver for the rear end of said guard to abut against, a latching connection intermediate

the ends of said guard to secure said guard to the receiver, coacting cam surfaces on said guard and receiver acting, when said guard is swung upwardly on its fulcrum, to impart slight forward movement of said guard with respect to the receiver, and when said guard is swung downwardly on said fulcrum, to impart slight rearward movement of said guard with respect to said receiver.

2. In a rifle in combination, a receiver, a trigger guard, means for detachably mounting said guard on said receiver comprising a tenon and groove connecting means between the receiver and front end of the guard, a pin and socket connecting means between said receiver and an intermediate portion of said guard, an abutment having a fixed relation to said receiver for the rear end of said guard to abut against, a latching connection intermediate the ends of said guard to secure said guard to the receiver, said latching connection being arranged so that when it is engaged a spring tension is imparted to the rear end of said guard against its abutment.

3. In a rifle in combination, a receiver, formed with a magazine well, a trigger guard extending forwardly beneath said magazine well to form a bottom therefor, means for detachably mounting said guard on said receiver comprising a tenon and groove connecting means between the receiver and front end of the guard, a pin and socket connecting means between said receiver and an intermediate portion of said guard, an abutment having a fixed relation to said receiver for the rear end of said guard to abut against, a latching connection intermediate the ends of said guard to secure said guard to the receiver, said latching connection being arranged so that when it is engaged a spring tension is imparted to the rear end of said guard against its abutment.

4. In a rifle in combination, a wooden stock, a receiver mounted above the same, and a detachable guard mounted below the same, a metal anchor device mounted in said stock to transmit recoil from said receiver to said stock, said anchor device extending vertically through said stock, and comprising a recoil member with a shouldered seat for engagement with the receiver, an anchor screw with its head in said seat and its lower end serving as an abutment for said guard, a nut for said anchor screw to adjustably tighten the stock against said recoil member, and means for detachably securing said guard to said receiver against the lower end of said anchor screw.

JOHN D. PEDERSEN.
